(57) **CLAIM**

The ornamental design for a card storage box, as shown and described.

DESCRIPTION

FIG. 1 is a top perspective view of the card storage box of the present invention with a transparent part inserted on the front and a cover attached to the top of the box;
FIG. 2 is a top perspective view thereof with the transparent part inserted on the front and the cover unattached and folded in a first configuration;
FIG. 3 is a top perspective view thereof with the transparent part raised and the cover unattached and folded in a second configuration;
FIG. 4 is a top perspective view thereof with the transparent part inserted on the front and the cover unattached below the box and folded in the first configuration;
FIG. 5 is a top perspective view thereof with the transparent part inserted on the front and the cover unattached and folded in a third configuration;
FIG. 6 is a top perspective view thereof with the transparent part inserted on the front and the cover attached to the bottom of the box; and,
FIG. 7 is a top perspective view thereof with the transparent part unattached and the cover unattached below the box and folded in a fourth configuration.
